(57) **CLAIM**

The ornamental design for the computer with in-and-out icon and slide in-and-out module, as shown and described.

DESCRIPTION

FIG. 1 is a top, front, and right side perspective view of a computer with in-and-out icon and slide in-and-out module showing our new design in an open state;

FIG. 2 is a top plan view thereof;

FIG. 3 is a bottom plan view thereof;

FIG. 4 is a left side view thereof;

FIG. 5 is a right side view thereof;

FIG. 6 is a rear view thereof;

FIG. 7 is a front view thereof;

FIG. 8 is an enlarged top, front, and right perspective view of the in-and-out module of FIG. 1 in open state with in-and-out icon in low light condition; and,

FIG. 9 is a top, front, and right side perspective view of the in-and-out module of FIG. 8 showing USB plugged in the in-and-out module with corresponding in-and-out icon in high light condition.

All of the features shown in broken lines are unclaimed. The broken lines radiating from the in-and-out icon in FIGS. 8 and 9 represent beams of light and form no part of the claimed design.
